(57) **CLAIM**

We claim the ornamental design for a model vehicle front bumper assembly, as shown and described.

DESCRIPTION

FIG. 1 is an upper, left, front perspective view of a model vehicle front bumper assembly, according to our new design; FIG. 2 is a front elevation view thereof; FIG. 3 is a rear elevation view thereof; FIG. 4 is a left side elevation view thereof; FIG. 5 is a right side elevation view thereof; FIG. 6 is an upper plan view thereof; FIG. 7 is a lower plan view thereof;

FIG. 8 is a lower, right, rear perspective view thereof; and, FIG. 9 is a lower, left, front perspective environmental use view of the model vehicle front bumper assembly.

In the drawings, the broken lines showing features of the model vehicle front bumper assembly form no part of the claimed design.

The broken lines in FIG. 9 depict environmental subject matter that form no part of the claimed design.
